UNITED STATES PATENT OFFICE.

LE ROY A. PRESCOTT, OF MUSKEGON, MICHIGAN, ASSIGNOR TO BENNETT PUMPS CORP., OF MUSKEGON, MICHIGAN, A CORPORATION OF MICHIGAN.

OIL-TANK BRACING.

Application filed June 11, 1928. Serial No. 284,494.

This invention relates to bracing for oil tanks. Oil tanks from which oil is pumped and dispensed, particularly for motor vehicle service, in large measure are of rectangular parallelopiped form having a horizontal base, parallel vertical sides, similar ends and a horizontal top. The area of the sides is large and the distance between the sides is relatively short as compared to the area and distance between the ends and a battery of the tanks are usually placed close together, each supplied with its own pump, it being necessary to have several of the tanks because of the several different grades of oil that are called for by motor vehicle users. Tanks of the shape described render it possible to economically conserve space, which would be wasted with cylindrical tanks or tanks of various other shapes.

The sides of the tanks being of considerable area and the tanks also being quite deep, when oil is placed within the tanks there is a tendency of the sides to bulge outwardly, the tanks being constructed of thin sheet metal. This causes the several tanks in the battery to separate at their upper and lower ends with the result that dirt and the like gets into the cracks between the tanks and the assembly is unsightly, while in many cases there is dispute as to the quantity of oil placed in a tank by an oil company, inasmuch as bulging sides act to cause the tank to hold more oil than its standard capacity. The present invention is directed to a very simple, practical and effective bracing for maintaining the spaced apart parallel sides of the tank in proper parallel relation to each other and preventing bulging outward and thus avoiding all of the troubles recited.

To this end I have made the invention defined in the following description, and shown in the accompanying drawing, in which,

Fig. 1 illustrates a battery of tanks located closely together as used in service.

Fig. 2 is a horizontal section through a tank equipped with the device of my invention.

Fig. 3 is a vertical section through a tank substantially on the plane of line 3—3 of Fig. 2, and,

Fig. 4 is a perspective view of one of the bracing units used in the invention.

Like reference characters refer to like parts in the different figures of the drawing. 55

The tank is made of sheet metal having parallel spaced apart vertical sides 1, parallel spaced apart vertical ends 2, a horizontal bottom 3 and a horizontal top 4. Several of the tanks comprising a battery thereof in service are located side by side so that the sides 1 of contiguous tanks are in direct contact, as shown in Fig. 1.

The bracing construction which I have provided for each tank includes two horizontal angle bars 5, one located at the inner side of each side 1 of the tank a short distance above the bottom and welded to the sides of the tank where the vertical flanges of said bars engage thereagainst. This is fully shown in Fig. 3.

Above the bars 5 and spaced apart in the length of the tanks are a plurality of vertical bracing units. Each of these units comprise two spaced apart vertical angle bars 6 connected by horizontal cross bars 7 of flat metal. The bars 6 have two flanges or legs 6^a and 6^b located at right angles to each other, the flanges 6^a bearing against the inner sides of the sides 1 of the tank and being welded or otherwise permanently fastened thereto, while the ends of bars 7 are welded or otherwise permanently connected to the inwardly extending flanges 6^b, as best shown in Fig. 2. The lower ends of the vertical bars 6 rest against the horizontal flanges of the bars 5 first described, as shown in Fig. 3, and said bars 6 extend substantially to the upper end of the tank. 75 80 85

The bracing structure described strengthens and reinforces the sides 1 of the tank, holding them rigidly against outward bulging and maintaining the same in true vertical planes irrespective of the quantity of oil which may be in a tank. As many of the vertical bracing units may be used in a tank as is required. Two of the same are shown in Fig. 2 but it is evident that with different dimensions of tanks a larger or a smaller number of the vertical bracing units may be used. 90 95 100

This invention while of simple character has proved very satisfactory and has solved the troubles previously encountered in oil tanks of the character described. The contiguous sides of a battery of tanks remain in 105

close contact throughout their entire surfaces. There is no bulging with unsightly dirt collecting cracks between the tanks, and the tanks being designed to contain a stipulated 5 quantity of oil, when said quantity is placed in a tank the tank is full thus eliminating all disputes with regard to short measure.

The invention is defined in the appended 10 claims and is to be considered comprehensive 15 of all forms of structure coming within the scope thereof.

I claim:

1. A tank having spaced apart parallel vertical sides and spaced apart vertical ends, the 15 areas of the sides of said tank being greater than the areas of said ends, and reinforcing means located within the tank comprising a vertical bar fixed to the inner side of each side of the tank and a cross bar connecting the opposite vertical bars.

2. A tank having spaced apart parallel vertical sides, ends and a top and bottom, said sides being of sheet metal, and reinforcing means located within the tank comprising 25 angle bars having flanges located at right angles to each other, one flange of one of said bars lying against and permanently secured to the inner side of each side of the tank and the other flange of each of said bars extending 30 inwardly, and a cross member connected at its ends to and extending between the inwardly extending flanges of said angle bars.

3. A tank comprising spaced apart vertical sides, ends, a top and bottom, said sides being 35 of sheet metal and of relatively large area compared to the area of the ends top or bottom, and a plurality of bracing units located within the tank and spaced from each other, each of said units comprising two spaced 40 apart parallel vertical bars and a plurality of cross bars connecting the vertical bars, said

vertical bars of each unit being located one against the inner side of each side of the tank and permanently secured thereto.

4. A construction containing the elements 45 in combination defined in claim 3, said vertical bars of the bracing units extending from the upper end of the tank to points located a distance above the bottom of the tank, and horizontal bars secured one at the inner side 50 of each side of the tank at the lower ends of the vertical bars of said bracing units.

5. A tank having spaced apart vertical sides, vertical ends and horizontal top and bottom, said sides of the tank being of sheet 55 metal and of relatively large area compared to the area of the ends, top and bottom, and bracing means located within the tank comprising horizontal angle bars located one against the inner side of each side of the tank, 60 each comprising a vertical flange lying against the inner side of a side of the tank and secured thereto, and a horizontal flange extending inwardly from the adjacent side of the tank, and a plurality of bracing units 65 within said tank located above said horizontal bars, each unit comprising two spaced apart vertical angle bars, each having one flange located against and permanently secured to the inner side of a side of the tank and a second flange extending inwardly from the adjacent side of the tank, and a plurality of flat bars of metal disposed between and connected at their ends to the inwardly extending flanges of said vertical bars, said vertical 70 bars at their lower ends lying above the horizontal flanges of the first mentioned angle bars and extending upwardly toward the upper end of the tank.

In testimony whereof I affix my signature.

LE ROY A. PRESCOTT.
